INVENTOR:

PETER HERRE,

BY Charles V. Tallyor

His ATTORNEY

UNITED STATES PATENT OFFICE

PETER HERRE, OF FICHTENAU, KREIS NIEDERBARNIM, GERMANY, ASSIGNOR TO
GENERAL ELECTRIC COMPANY, A CORPORATION OF NEW YORK

STEM MAKING MACHINE

Application filed March 18, 1930, Serial No. 436,877, and in Germany April 6, 1929.

My invention relates to machines for making stems for electric incandescent lamps and similar articles. Such stems ordinarily comprise a stem or flare tube, an exhaust tube and 5 leading-in conductors having portions thereof sealed in a stem press which unites the stem or flare tube and exhaust tube and portions extending therebeyond to which a filament may be united. It is often necessary 10 that the filament receiving ends of the lead wires be more widely separated than the outer portions of said wires. Heretofore this has been accomplished by the insertion of bent leads in a flare tube which had been partially flattened and widened at its inner end. 15 My invention provides means whereby such stems are produced without necessitating such pre-bending of the leads or flattening of the flare tube end.

20 In the drawings, Fig. 1 comprises a plan and side elevation of flare tubing which may be used according to my invention; Fig. 2 comprises a plan and side elevation of flare tubing formerly used; Fig. 3 is a schematic plan view of a machine comprising my invention; Fig. 4 is a front elevation of a portion of a head; Fig. 5 is a side elevation thereof partially in section; Fig. 6 is a section on the line 6—6 thereof; and Figs. 7 to 10 are 25 side elevations showing various positions of the operating parts.

In Figs. 1 and 2 are shown the flare tube and leading-in wire assemblies used according to my invention and according to prior 30 practice. My invention is incorporated in each head of the machine schematically shown in Fig. 3 and acts in cooperation with the stem forming operations of this machine. This machine is intermittently indexed and 35 performs the following operations at the positions indicated.

At position A, exhaust tube 13 is placed 40 within the jaws 14 in the arms 15 as more clearly shown in the enlarged machine head 45 shown in Figs. 4 and 5. At the next position, B, a flare tube 10 slides down the rods 16 and into the jaws 17 of the machine head. The leading-in wires 18 are next put in the 50 head at position C, their lower ends resting against the shoulders 19 (Figs. 4, 5 and 6)

of the levers 20 and 21, and their middle portions passing through the slotted guide arms 22 and 23 of these levers. The pin 12 definitely locates the upper ends of the levers 20 and 21.

Before the head is indexed to position D, the leading-in wires are forced against the center portions of the guide slots and clamped by the ends 24 and 25 of the levers 26 and 27. Both sets of levers 20, 21 and 26, 27 are 55 operated in the slot 28 in the carriage 29 on the pins 30, 31, 32 and 33 respectively by the action of the springs 34 and 35 respectively. The outer set of levers 26 and 27 is kept open during the insertion of the leading-in wires by the plunger 36 whose prongs 37 and 38, when the plunger is in its highest position, bear against the balls 39 in the lower ends of the said levers. To clamp the leading-in 60 wires the rod 40, on which the plunger is fastened, is lowered clear of the ends of the levers. The mechanism is held in a definite position by the carriage 29 which is fastened to the rigid arms 41 by the bolts 42. The stem parts are thus securely held by the machine 65 head and my device passes on through the following three positions D, E and F where the lower ends of the flare tubing 10 and the exhaust tube 13 are acted upon by the burners 43 to form the stem press 44. The change 70 that has taken place in the stem can be readily seen by comparing Figs. 7 and 8.

Midway between positions F and G there is mounted the cam 45 over which the rollers 46 upon the pin 47 travel during the indexing 75 period of the machine. Because of the particular shape of the cam 45 (Fig. 9) the pin 47 which rides in the vertical slot 48 will be moved upward and the levers 20 and 21 will 80 be spread. The spreading of the levers is produced by the pin 47 when it enters the narrow channel between the levers bounded by their humps 49 and 50. The leading-in 85 wires which are still clamped by the outer levers 26 and 27 are thereby bent outwards and this is accompanied by a widening of the softened lower part of the stem press. Before the rollers 46 have passed beyond the end 90 of the cam 45, the plunger 36 is raised spread- 95 against the shoulders 19 (Figs. 4, 5 and 6) 100

ing the outer jaws and releasing the leading-in wires as shown in Fig. 10.

At the following position, G, the clamps 51 and 52 press against the sides of the stem 5 press 44 and flatten it. At positions H, J, and K, the stem is annealed and at position L, the complete stem is removed from the machine. Between positions L and M are located the cams 53 the under surfaces of which 10 are engaged by the rollers 46 and are thereby drawn to their lower positions allowing the levers 20 and 21 to come together.

What I claim as new and desire to secure by Letters Patent of the United States is:

- 15 1. In a stem machine, the combination of jaws for supporting an assembly comprising a glass tube and leading-in wires extending longitudinally therefrom of a pair of levers having guide arms extending therefrom between said leading-in wires and shaped to receive portions of said leading-in wires, another pair of levers disposed outside said leading-in wires and having portions thereof shaped to clamp said wires against said guide arms, a pin movably mounted between said first mentioned pair of levers, a cam for moving said pin and a member for moving said second mentioned levers to cause said clamping portions thereof to open or close, said first mentioned levers being shaped so that movement of the aforesaid pin causes said guide arms to approach each other or separate depending on the direction of said movement.
- 20 2. In a stem machine, the combination of jaws for supporting an assembly comprising a glass tube and leading-in wires extending longitudinally therefrom of a pair of pivoted levers having guide arms extending therefrom between said leading-in wires and shaped to receive portions of said leading-in wires, another pair of pivoted levers disposed outside said leading-in wires and having portions thereof shaped to clamp said wires against said guide arms, a pin movably mounted between said first mentioned pair of levers, a cam for moving said pin and a member for moving said second mentioned levers to cause said clamping portions thereof to open or close, said first mentioned levers being shaped so that movement of the aforesaid pin causes said guide arms to approach each other or separate depending on the direction of said movement.
- 25 3. In a stem machine, the combination of jaws for supporting an assembly comprising a glass tube and leading-in wires extending longitudinally therefrom of a pair of pivoted levers having guide arms extending therefrom between said leading-in wires and shaped to receive portions of said leading-in wires, another pair of pivoted levers disposed outside said leading-in wires and having portions thereof slotted to clamp said wires against said guide arms, a pin movably

mounted between said first mentioned pair of levers, a cam for moving said pin and a member for moving said second mentioned levers to cause said clamping portions thereof to open or close, said first mentioned levers having humped portions so that movement of the aforesaid pin causes said guide arms to approach each other or separate depending on the direction of said movement.

In witness whereof, I have hereunto set my hand this 4th day of March, 1930.

PETER HERRE.
